ABSTRACT

'CARZ0002' is a product of a planned breeding program. The new cultivar 'CARZ0002' has medium sized cranberry and white bi-colored flowers, excellent flower production, moderate plant size and uniform mounding and somewhat spreading habit with medium green foliage.

1 Drawing Sheet

1

Latin name of the genus and species of the plant claimed:
Catharathus roseus.

DETAILED DESCRIPTION

Catharanthus variety 'CARZ0002' disclosed in the present application has shown uniformity and stability, as described in the following section. *Catharanthus* variety 'CARZ0002' disclosed in the present application has been asexually reproduced a sufficient number of generations with careful attention to uniformity of plant type and has been increased with continued observation for uniformity.

Origin of 'CARZ0002'

'CARZ0002' is a product of a planned breeding program. The new cultivar 'CARZ0002' has medium sized cranberry and white bi-colored flowers, excellent flower production, moderate plant size and uniform mounding and somewhat spreading habit with medium green foliage.

'CARZ0002' originates from a planned self-pollination in an indoor greenhouse in August 2015 in Gilroy, California. The parent was identified as 'FF 1835-1', having medium flowers of rose and white bi-color and upright habit compared to 'CARZ0002'.

The seed was sown in March 2016 in a greenhouse in Gilroy, California. 'CARZ0002' was selected as a single flowering plant within the progeny of the stated self-pollination in March 2017.

The first act of asexual reproduction of 'CARZ0002' was accomplished when vegetative cuttings were propagated from the initial selection in January 2019 in a greenhouse in Gilroy, California.

Horticultural examination of plants grown from cuttings of the original plant in January 2019, in Gilroy, California, and continuing thereafter, has demonstrated that the combination of characteristics as herein disclosed for 'CARZ0002'

2

are firmly fixed and are retained through successive generations of asexual reproduction.

'CARZ0002' has not been observed under all possible environmental conditions. The phenotype may vary significantly with variations in environment such as temperature, light intensity, disease exposure, and day length.

TABLE 1

10 DIFFERENCES BETWEEN THE NEW VARIETY 'CARZ0002' AND A MOST SIMILAR VARIETY		
	'CARZ0002'	'Titan Cranberry', Protected under U.S. Pat. No. 10,212,908
15	Flower color:	Cranberry color on outer edge of petals with white color on inner part of petals with a white eye
20	Disease resistance:	Known disease resistance to <i>Phytophthora nicotianae</i>
25	Plant habit:	Mounded and somewhat spreading

BRIEF DESCRIPTION OF THE FIGURES

FIG. 1 shows a close view of an inflorescence. Taken on Jan. 3, 2023 in Gilroy, CA.

FIG. 2 shows a whole flowering plant. Taken on Jul. 25, 2022 in Monroeville, NJ.

The plant descriptions and measurements were taken in Gilroy, California in April 2024. The plants were approximately 14 weeks old and were growing in 4.5" pots in a greenhouse. The color descriptions provided are in reference to The R.H.S. Colour Chart, Sixth Edition (2015).
Plant:

<i>Form, growth and habit.</i> —Semi-woody, grown as an annual; mounding and somewhat spreading habit; very well branched.		<i>Petal width.</i> —3.0-3.6 cm.
<i>Plant height.</i> —24 cm.		<i>Petal eye zone diameter.</i> —0.6-1.2 cm.
<i>Plant height (inflorescence included).</i> —25 cm.	5	<i>Young floret, color upper surface.</i> —RHS 61B and RHS NN 155D.
<i>Plant width.</i> —30 cm.		<i>Young floret, color lower surface.</i> —RHS 72A and RHS 69D.
<i>USDA hardiness.</i> —10-11.		<i>Mature florets, color upper surface.</i> —RHS 61B and RHS NN 155D.
Roots:		<i>Mature floret, color lower surface.</i> —RHS 72A and RHS 69D.
<i>Description.</i> —Fibrous, freely branching.		<i>Apex shape.</i> —Cuspidate.
<i>Habit.</i> —Taproot with smaller, branching lateral roots.	10	<i>Degree of lobation.</i> —Deep.
<i>Color.</i> —Closest to RHS NN 155C.		<i>Margin.</i> —Crenate.
Foliage:		<i>Base.</i> —Fused.
<i>Type.</i> —Opposite.		<i>Texture, upper surface.</i> —Smooth.
<i>Immature, leaf color, upper surface.</i> —Closest to RHS 144A.	15	<i>Lower surface.</i> —Smooth.
<i>Lower surface.</i> —Closest to RHS 146B.		<i>Tube, color outer surface.</i> —Closest to RHS 184A and RHS 145B.
<i>Mature, leaf color, upper surface.</i> —Closest to RHS 141A.		<i>Tube, color inner surface.</i> —Closest to RHS 184A and RHS 145B.
<i>Lower surface.</i> —Closest to RHS 143A.	20	<i>Tube, length.</i> —2.5-3.0 cm.
<i>Vein color, upper surface.</i> —Closest to RHS 145A.		<i>Tube, diameter (at opening).</i> —0.20 cm.
<i>Vein color, lower surface.</i> —Closest to RHS 145D.		<i>Tube, texture outer surface.</i> —Smooth.
<i>Length.</i> —10.0-13.0 cm.		<i>Inner surface.</i> —Smooth.
<i>Width.</i> —2.5-4.5 cm.		<i>Bract number per flower.</i> —0.
<i>Shape.</i> —Ovate.	25	<i>Sepal number per flower.</i> —5.
<i>Base shape.</i> —Acute.		<i>Sepal shape.</i> —Lanceolate.
<i>Apex shape.</i> —Acuminate.		<i>Sepal margin.</i> —Smooth.
<i>Margin.</i> —Entire.		30 Bud (just before opening):
<i>Texture, upper surface.</i> —Smooth.		<i>Color.</i> —RHS 77B and RHS 145D.
<i>Texture, lower surface.</i> —Smooth.		<i>Length.</i> —1.8 cm.
<i>Pattern of veining.</i> —Pinnate.		<i>Width.</i> —0.6 cm at the widest point.
<i>Petioles color.</i> —Closest to RHS 142B.		<i>Shape.</i> —Tubular.
<i>Petioles length.</i> —0.4-1.4 cm.		35 Bract:
<i>Diameter of petiole.</i> —20 cm.		<i>Color.</i> —Closest to RHS 184A and RHS 145A.
<i>Texture (upper and lower surface).</i> —Smooth.		<i>Length.</i> —0.7-1.1 cm.
Stem:		<i>Diameter.</i> —0.15-0.2 cm.
<i>Color of stem.</i> —Closest to RHS 142B.		<i>Texture, upper surface.</i> —Hirsute.
<i>Length of stem.</i> —20-25 cm.		<i>Lower surface.</i> —Hirsute.
<i>Diameter.</i> —0.4-0.6 cm.		40 Calyx:
<i>Length of internodes.</i> —3.0-6.5 cm.		<i>Number of sepals.</i> —5, fused sepals forming a short tube around the base of the floret.
<i>Texture.</i> —Smooth.		<i>Color of sepals.</i> —RHS 145A.
Inflorescence:		<i>Length of sepals.</i> —0.2-0.3 cm.
<i>Type.</i> —Panicle.		<i>Width of sepals.</i> —0.1 cm.
<i>Blooming habit.</i> —Flowers continuously from spring through fall.	45	<i>Apex shape.</i> —Obtuse.
<i>Number of open flowers per inflorescence.</i> —About 2-6.		<i>Apex margins.</i> —Entire.
<i>Quantity of inflorescences per plant.</i> —About 24-36.		<i>Texture, outer surface.</i> —Pubescent.
<i>Lastingness of individual blooms on the plant.</i> —About 2 weeks (depending on temperatures).		<i>Inner surface.</i> —Glabrous.
<i>Fragrance.</i> —Rose.	50	Reproductive organs:
Flower:		Gynoecium
<i>Arrangement.</i> —Arising from upper leaf axils, freely flowering, facing upwards and outwards.		<i>Pistil quantity.</i> —One.
<i>Floret form.</i> —Single salverform, tube with disc of petals.	55	<i>Length.</i> —0.35 cm.
<i>Length of floret.</i> —6.1 cm.		<i>Style color.</i> —RHS 159D.
<i>Width of floret.</i> —6.1 cm.		<i>Style length.</i> —0.2 cm.
<i>Depth of floret.</i> —2.8 cm.		<i>Stigma color.</i> —RHS 144B.
<i>Peduncle length.</i> —0.3 cm.		<i>Ovary color.</i> —RHS 144A.
<i>Peduncle diameter.</i> —0.2 cm.		<i>Ovary length.</i> —0.1 cm.
<i>Peduncle texture.</i> —Smooth.		<i>Ovary diameter.</i> —0.05 cm.
<i>Peduncle color.</i> —RHS 141C.		60 Androecium
<i>Petal arrangement.</i> —Overlapping.		<i>Stamen quantity.</i> —4.
<i>Petal number.</i> —5.		<i>Color of filaments.</i> —RHS 159D.
<i>Petal shape.</i> —Obovate.		<i>Length filaments.</i> —0.05 cm.
<i>Petal length.</i> —2.9 cm.	65	<i>Anther color.</i> —RHS 164A.
		<i>Length of anthers.</i> —0.1 cm.

US PP36,790 P2

5

Color of pollen.—RHS 10D.

Pollen amount.—Normal.

Fertility/seed set.—Male and female fertile, moderate seed set.

Typical seed number.—10-20.

Seed length.—0.3 cm.

Seed width.—0.1-0.2 cm.

Seed color.—RHS 203A.

6

Disease/pest resistance.—Exhibits strong resistance to aerial phytophthora (*Phytophthora nicotianae*); insect pest resistance not observed.

What is claimed is:

- 5 1. A new and distinct cultivar of *Catharanthus* plant named 'CARZ0002', substantially as illustrated and described herein.
